CLAIM

The ornamental design for a bone conduction headphone charger, as shown and described.

DESCRIPTION

FIG. 1 is a front perspective view of a bone conduction headphone charger showing my design.

FIG. 2 is a rear perspective view of the bone conduction headphone charger in FIG. 1.

FIG. 3 is a front elevation view of the bone conduction headphone charger in FIG. 1.

FIG. 4 is a rear elevation view of the bone conduction headphone charger in FIG. 1.

FIG. 5 is a left side elevation view of the bone conduction headphone charger in FIG. 1.

FIG. 6 is a right side elevation view of the bone conduction headphone charger in FIG. 1.

FIG. 7 is a top plan view of the bone conduction headphone charger in FIG. 1; and,

FIG. 8 is a bottom plan view of the bone conduction headphone charger in FIG. 1.

The broken lines in the drawings are employed to show unclaimed portions of the bone conduction headphone charger, and form no part of the claimed design.

1 Claim, 8 Drawing Sheets
